UNITED STATES PATENT OFFICE.

JOHN W. WEBB, OF CHICAGO, ILLINOIS, ASSIGNOR TO THE CONTAINER CLUB, OF CHICAGO, ILLINOIS, A CORPORATION OF DELAWARE.

PAPER-TESTING MACHINE.

Application filed December 19, 1921. Serial No. 523,308.

To all whom it may concern:

Be it known that I, JOHN W. WEBB, a citizen of the United States, residing at Chicago, in the county of Cook and State 5 of Illinois, have invented certain new and useful Improvements in Paper-Testing Machines, of which the following is a specification.

My invention relates to improvements in 10 a machine which is designed for the testing of sheet materials, such as paper, parchment, cardboard and other varieties of fibre board, and like materials, and which is of a type in which a body of liquid arranged 15 to be put under increasing measured pressure is arranged to exert its stress through a rubber diaphragm against the sheet material, backed on its opposite side by an oriented clamping plate or clamping head 20 which is arranged to clamp the material down on a table having in its upper face an orifice exposing the rubber diaphragm and registering with the orifice in the head. In machines of this type as heretofore con- 25 structed the registering orifices exposing the part of material subjected to a test have been circular in outline, and in making tests of fibrous material having a striated structure, because of the parallel arrangement of 30 a greater or less proportion of the fibres, the break occurs transversely of the direction of the fibres. This is due to the fact that the fibres will spread or yield in the transverse direction to a greater extent 35 transversely of the fibres than in the direction of their length, so that when the limit of their strength is reached in making a test they abruptly snap, and as the break of the parallel fibres tends to occur 40 about midway between the points at which they are clamped, the rupture of the paper ordinarily takes the form of a break extending transversely of the grain of the paper diametrically across the orifice of the 45 clamping plate. It is obvious that the indication of the strength of the paper thus afforded is the tensile strength of the parallel fibres, and that if the paper is extremely fibrous, and consequently relatively weak 50 across the grain, the indicated bursting

strength will be deceptive. It is important for many purposes to know whether a paper is well matted and possesses a uniform breaking strength in all directions, and my invention relates to a form of orifice in 55 the clamping head or die which will discriminate between the strength of the material lengthwise of the fibres and its strength transversely, the essential elements of my invention being more particularly 60 pointed out in the appended claims.

In the accompanying drawing Fig. 1 is a side elevation of a testing machine of well-known form to which my invention is adapted to be applied; Fig. 2 is a vertical 65 section through the clamping head of such a machine in which my invention has been incorporated; Fig. 3 is a fragmentary top plan view of the clamping table of the machine shown in Fig. 2, parts above the table 70 being omitted; Fig. 4 is a vertical section corresponding to Fig. 2 but illustrating a detachable clamping plate adapted to be attached to the standard parts of an ordinary testing machine and constituting a 75 modified form of my invention; Fig. 5 is a perspective view of a rubber diaphragm adapted to be used in a machine employing my invention; and Fig. 6 is a face view of a portion of a diaphragm of somewhat different form from that shown in Fig. 5. 80

The same reference characters indicate the same parts in all the figures of the drawing.

For the purpose of rendering an explanation fully intelligible I have illustrated 85 in Fig. 1 a well-known form of testing machine to which my present invention is applicable, although the specific construction of the greater part of the machine is immaterial to this invention. It will suffice to 90 explain briefly that the base 1 of the machine supports a suitable body 2 and bracket 3, the body being formed with a cylinder arranged to receive a piston 4 operated by the handwheel 5 to place a body of suitable 95 liquid, such as glycerine, in the cylinder under pressure, a pressure gauge 6 being provided to indicate the pressure as the handwheel is turned to increase it in making a test. The cylinder is in communica- 100

tion with a vertical passage 7 (see Fig. 4) terminating at the top in a wide shallow chamber 8 closed by the rubber diaphragm, which latter is clamped in the frame structure by an orificed clamping member constituting the supporting table 9.

The bracket 3 is arranged to support a vertical, manually-operable screw shaft 10 equipped with a clamping head or backing member 11 having an orifice registering with the orifice in the supporting tables.

All the parts thus far described are old in the art, and it will be understood that as heretofore invariably constructed the aperture above the rubber diaphragm in the clamping table and the orifice in the clamping head are circular, and the rubber diaphragm exhibits in diametrical cross-section the outline shown in Figure 4, slightly thickened at the center, so that a circular section of the material being tested is subjected to the action of the machine.

In a machine constructed according to my present invention the pressure head which constitutes the backing member for holding the paper down on the paper table above the diaphragm is formed with an elongated orifice or aperture 12, see Fig. 2, and the table member 13 is formed with a registering orifice 14 of the same size and shape. See Figs. 2 and 3. The rubber diaphragm 15 is preferably formed with an elongated rounded projection 16 on its upper face slightly smaller than the orifices 12 and 14, and having a semi-cylindrical middle portion merging into spherically-shaped ends.

In order to prevent rotation of the clamping head 11 (which ordinarily is merely swiveled to the screw shaft 10, its angular position being immaterial with a round orifice) I have provided a guide 17 to maintain a fixed angular relation of the head and the aperture 12 therein with reference to the frame of the machine, so that the apertures 12 and 14 will always register and remain angularly invariable and the material to be tested can be clamped in position either with its fibres disposed parallel to the orifices and projection 16, or transversely thereof. In either case the line of break when the paper ruptures at the conclusion of a testing operation will extend longitudinally of the orifices, but it will require greater pressure to break the fibres on a line extending transversely of their direction than to burst through them in a line extending in the direction of their length, thus affording means for obtaining indications showing the comparative strength of the paper, with the grain and across it.

The shape of the orifices 12 and 14 and the projection 16 of the rubber diaphragm as shown in Figs. 2 and 3, with parallel sides and rounded ends, may be varied somewhat, and in Fig. 6 I have shown a projection 18

which is of elliptical outline and is intended to be employed with a clamping head of corresponding shape.

In Fig. 4 I have shown a detachable clamping plate 19 adapted to be secured to the clamping head 11, which constitutes part of a machine of ordinary construction and is formed with a circular orifice 11^a. In such a case the orifice 20 above the rubber diaphragm may also be the rounded orifice used in the regular supporting table member 9. Preferably a pair of rubber diaphragms 22 of standard construction are employed. The orifice 19^a of the detachable clamping plate is of elongated form, such as shown in Figs. 2 and 3 (or of the elliptical form shown in Fig. 6) and the action of the parts of the machine so constructed is the same, or substantially the same, as that of the forms of my invention above described.

I claim:

1. In a machine of the character described and having a means for creating and measuring liquid pressure and a diaphragm exposed to liquid pressure, material-holding means including a backing member formed with an elongated orifice opposite the field of pressure of said diaphragm.

2. In a machine of the character described and having means for creating liquid pressure and measuring such pressure and an orificed paper-supporting table and an elastic diaphragm covering said orifice and exposed to liquid pressure on its inner side, material-holding means including a clamping head having an elongated orifice opposite the orifice in said table.

3. In a machine of the character described and having means for creating liquid pressure and means for measuring such pressure and an orificed paper-supporting table and an elastic diaphragm covering said orifice and exposed to liquid pressure on its inner side, material-holding means including an orificed clamping head, the orifices in said table and said head being elongated and registering with each other.

4. In a machine of the character described and having means for creating liquid pressure and means for measuring such pressure and an orificed paper-supporting table and an elastic diaphragm covering said orifice and exposed to liquid pressure on its inner side, material-holding means including an orificed clamping head, the orifices in said table and said head being elongated and having parallel sides and rounded ends registering with each other.

5. In a machine of the character described and having means for creating liquid pressure and means for measuring such pressure and a rubber diaphragm exposed on one face to the liquid pressure and having on its opposite face an elongated projection, mate-

rial-holding means including a backing member formed with an elongated orifice adapted to receive said projection.

6. In a machine of the character described and having means for creating liquid pressure and means for measuring such pressure and a rubber diaphragm exposed on one face

to the liquid pressure and having on its opposite face an elongated projection, having a rounded face, material-holding means, including a backing member formed with an elongated orifice adapted to receive said projection. 10

JOHN W. WEBB.
